STEAM OR AIR ENGINE OF THE OSCILLATING CYLINDER TYPE

Filed March 18, 1947

2 SHEETS—SHEET 2

that since the circular lugs 6, 6' are fixed to the cranks 3, 3' and the connecting rods 8, 8' are eccentrically pivoted to the circular lugs, the ends of the connecting rods will carry out a reciprocating movement between the two arms of the guides 2, 2' as the cranks 3, 3' are rotated, with the result that when either piston is at the extremity of its travel the two arms of its guide member 2 will be in such a position as to ensure that inlet and exhaust ports are already nearly fully open.

With this arrangement, a rapid opening and closing of the ports will be effected during the stroke of the piston, and before it reaches the end of its travel.

It will be understood that the amount of oscillation of the cylinder will be determined by the position of the lug on the crank, and that the amount of off-set from dead centre which the connecting rod will assume at the extremity of the piston's travel, will be determined by the diameter of the circular lug which forms the eccentric and/or by the position on this lug at which the connecting rod is eccentrically pivoted. The diameter of the circular lug, however, must in addition be determined by the distance apart of the two arms of the guide member in order that these arms may be continually in contact with the lug so that an efficient oscillating movement of the cylinder is effected.

I claim:

1. Steam or air engine comprising a cylinder pivotally mounted in front of a port face, a piston having a piston rod connected thereto, slidably mounted within said cylinder, a connecting rod pivoted at one end to a cross-head secured to said piston rod and pivoted at the other end to a circular lug disposed on the face of a circular crank and a pair of parallel arms extending from said cylinder on opposite sides of said circular lug, said connecting rod being eccentrically pivoted to said circular lug, and said circular lug being disposed eccentrically with respect to the axis of rotation of said crank, whereby as the piston reciprocates said cylinder is oscillated over

said port face and the opening and closing of the ports is effected before the piston reaches the end of its stroke.

2. Steam or air engine comprising a cylinder pivotally mounted in front of a port face, a piston having a piston rod connected thereto, slidably mounted within said cylinder, a connecting rod pivoted at one end to a cross-head secured to the piston rod and pivoted at the other end to an actuating member eccentrically disposed on a circular crank mounted on the engine crank-shaft, and a pair of parallel arms extending from said cylinder on opposite sides of said actuating member, whereby as the piston reciprocates the cylinder is oscillated over said port face and the opening and closing of the ports is effected before the piston reaches the end of its stroke.

3. Steam or air engine comprising a cylinder pivotally mounted in front of a port face, a piston having a piston rod connected thereto, slidably mounted within said cylinder, a connecting rod pivoted to the piston rod and operatively connected with the engine crank-shaft, a guide member extending from said cylinder and engaging with an actuating member mounted on said crank-shaft, one end of said piston rod being pivotally connected to one end of said connecting rod, the other end of which is eccentrically pivoted to said actuating member whereby as the piston reciprocates the cylinder is oscillated over said port face and the opening and closing of the ports is effected before the piston reaches the end of its stroke.

HAROLD ERNEST FLORY.
